UNITED STATES PATENT OFFICE.

JOHN B. MURRAY, OF WILMINGTON, ILLINOIS.

RAIL JOINT.

Application filed June 8, 1922. Serial No. 566,774.

To all whom it may concern:

Be it known that I, JOHN B. MURRAY, a citizen of the United States, and a resident of Wilmington, in the county of Will and 5 State of Illinois, have invented a new and useful Improvement in Rail Joints, of which the following is a full, clear, and exact description.

My invention relates to improvements in 10 rail joints, and it consists in the combinations, constructions, and arrangements herein described and claimed.

An object of my invention is to provide an improvement over that form of the device shown in my prior Patent No. 1,413,765. In said prior patent I disclosed a rail joint which comprises two pieces that grips the rail at the junction of two sections, the members being secured to each other by two bolts 20 and being fashioned so as to create an upward leverage upon the rail sections as the trains pass thereover. The construction of the present device is primarily designed to provide a longer leverage to the two members, whereby a greater lifting force is exerted by the device when a train passes 25 thereover.

A further object of my invention is to provide a rail joint which does away with 30 the portions projecting between the rail sections, as disclosed in my patented device.

A further object of my invention is to provide a device of the character described in which only one bolt is used to secure the 35 two members together.

A further object of my invention is to provide a device of the character described which supports the rail sections in only two points.

40 A further object of my invention is to provide a device of the character described which is simple in construction and durable and efficient for the purpose intended.

A further object of my invention is to 45 provide a device of the character described which may be readily attached to a railroad track without any alterations in the latter being necessary.

Other objects and advantages will appear in the following specification, and the 50 novel features of the invention will be particularly pointed out in the appended claims.

My invention is illustrated in the accompanying drawings, forming part of this 55 application, in which

Figure 1 is a side elevation of the device

as shown operatively applied to a railroad track,

Figure 2 is a section along the line 2—2 of Figure 1, and

Figure 3 is a plan view of one of the members of the device.

In carrying out my invention, I make use of two sections 1 and 2 of an ordinary railroad track, these sections being supported by ties 3 in the customary manner. The device comprises two members which are identical with respect to each other and a description of one of the members will therefore suffice for both members. In Figure 3 it will be noted that the member B is provided with two arms 4 which are adapted to straddle the web 5 of the section 2. The arms 4 have an upwardly extending projection 6 adjacent to their inner ends and a downwardly extending projection 7 adjacent to their outer ends. The projections 6 are adapted to engage with the under side of the head 8 of the rail, and the projections 7 are adapted to engage with the flange 9 of the rail. The arms 4 are cast integrally with a depending portion 10 (see Figure 2).

The portions 10 of the members A and B are adapted to abut each other along the line 11. It will be seen from Figure 1 that the adjacent surfaces of the portions 10 slope gently away from the line 11 and that therefore the two members A and B may swing with respect to each other, the line 11 acting as a fulcrum for the members. The member B has pins 12 which are adapted to enter recesses 13 in the member A, whereby the two members are prevented from lateral movement with respect to each other. In Figure 3 I have shown the portion 10 as being provided with a base 14, the base supporting the base 9 of the rail. The portions 10 also have aligned openings 15 through which a bolt 16 is disposed. From this construction it will be apparent that by merely tightening the bolt 16, the sections 1 and 2 of the rails are forced upwardly at their adjacent ends.

From the foregoing description of the various parts of the device, the operation thereof may be readily understood. The members A and B are slid onto the sections 1 and 2 and are secured in place by bolts 17 which are disposed in slots 18 of the arms 4 and in the ordinary openings provided in the rail sections 1 and 2. In this manner the members A and B are adapted to move longi-

tudinally with respect to each other and at the same time are prevented from lateral movement. As heretofore stated, the pins 12 and the bolt 16 also prevent the members 5 A and B from lateral movement with respect to each other. It is obvious therefore that the members are secured to each other in the minimum amount of time, since only three bolts have to be assembled to the members 10 in order to secure the members in place.

When a train passes over the adjacent ends of the sections 1 and 2, the weight of the load tends to force the ends of the rail sections downwardly. The weight is carried by the projections 6 and tends to force the lower ends of the portions 10 apart, the line 11 acting as a fulcrum. This movement is prevented by the bolt 16 which securely holds the portions 10 from movement in an outward direction. The force of the weight is transmitted to the portions of the sections of the rails which are removed from the adjacent ends of the rails by the engagement of the projections 7 with the 25 flanges 9 of the rails. In this manner the weight of the train passing over the rail sections is evenly distributed throughout a greater portion of the ties than is possible with the ordinary fish-plate. The adjacent 30 ends of the sections 1 and 2 may be lifted by the members A and B when the bolt 16 is tightened. In this manner wear between the members A and B is readily taken up.

The device performs a simple means by 35 which the downward play of the sections 1 and 2 is prevented when a railroad train passes thereover. As heretofore stated, the device is simple in construction, durable and efficient for the purpose intended, and 40 is not likely to easily get out of order.

I claim:

1. The combination with the adjacent ends of two rail sections, said sections being adapted to abut each other, of rail connecting members disposed on said sections, said members having their adjacent faces abutting along a horizontal line, and having depending portions disposed beneath said rail sections, and a bolt connecting said members together adjacent to the lower ends of 50 said depending portions.

2. The combination with two rail sections adapted to abut each other, connecting members secured to both sections and adapted to abut each other along a horizontal line disposed midway between the top and bottom of said rail sections, whereby said members are adapted to swing about the line as a fulcrum, integral depending portions carried by said members and disposed beneath said 60 rail sections, and a bolt connecting said depending portions together adjacent to the lower ends thereof.

3. The combination with two rail sections adapted to abut each other, connecting members secured to both sections, said members having integral arms adapted to straddle the webs of said rail sections, and having depending portions adjacent to their inner ends, said arms having upwardly extending 70 projections adjacent to their inner ends, and having downwardly extending projections disposed adjacent to their outer ends, said members having their adjacent surfaces fashioned so as to abut one another along a 75 horizontal line, a bolt connecting said depending portions together, and pins carried by one of said members and being adapted to enter recesses in the other member.

JOHN B. MURRAY.
